UNITED STATES PATENT OFFICE.

HARRY H. McCARN, OF SEATTLE, WASHINGTON.

DRY-PIPE VALVE.

1,420,269.

Specification of Letters Patent. Patented June 20, 1922.

Application filed December 2, 1920. Serial No. 427,775.

To all whom it may concern:

Be it known that I, HARRY H. McCARN, a citizen of the United States, residing at Seattle, in the county of King and State of Washington, have invented certain new and useful Improvements in Dry-Pipe Valves; of which the following is a specification.

The present invention consists of a dry pipe valve for use on sprinkler systems of fire alarms and aims primarily to provide a valve of this type which will be simple of construction and which will positively operate to initiate a flow of water and sound an alarm.

Another object of the invention is to so construct the valve and valve seat that the pressure of the water will augment retention of the valve on the seat until the pressure of air in the air chamber has been reduced to a minimum.

The above and other objects of this invention will be in part described and in part understood from the following description of the present preferred embodiment of the invention taken in connection with the accompanying drawings, wherein:

Fig. 1, is a vertical sectional view of a valve constructed in accordance with this invention, and

Fig. 2, is a horizontal sectional view thereof taken on the line 2—2 of Fig. 1, and looking in the direction of the arrows.

A valve casing generally designated 3 is provided which may be of any desired configuration and preferably consists of a lower section 4 which has detachably superimposed thereon an upper section 5. The lower section 4 has a water inlet opening 6 formed in the bottom thereof, which inlet is provided with a lateral opening 7 which constitutes a drain. The lower section 4 of the casing is hollow and constitutes the main portion of the water chamber 8.

The upper section 5 of the valve casing has a vertical partition 9 formed therein which extends across the casing and is provided with an oblique opening 10 approximately midway its ends. The partition 9 is continued downwardly into the water chamber 8 and is then curved upwardly into a substantially semicircular shape in cross-section to provide a channel 11. One side 12 of the upper section 5 constitutes the main air chamber while the compartment on the opposite side of said partition comprises an auxiliary air chamber 13. An opening 14

extends from the air chamber 12 and, as shown to advantage in Fig. 1 of the drawings, is in vertical alignment with the opening 6 of the water chamber. The auxiliary air chamber 13 has a lateral opening 15 formed therein which may lead to any suitable mechanism which may sound an alarm when water passes therethrough from the chamber 8.

A valve unit generally designated 16 is mounted in the casing and consists of a semi-circular arm, the opposite ends of which are of a spherical configuration as indicated at 17. One of said ends is depressed into one face of a valve head 18 hereinafter referred to as the air valve, while the opposite end is depressed into one face of a valve head 19, the latter being hereinafter referred to as the water valve. The air valve 18 is arranged to fit snugly on a valve seat 20, the latter having an annular groove 21 formed therein which communicates with a bypass 22 which extends through the wall of the upper section of the casing. In this way leakage through the valve will be drained off without opening the valve or without interfering with the use of the latter. A suitable valve seat 23 is provided for the water valve 19 and consists of a pair of annular rings, the lower faces of which are enlarged and preferably made of a yieldable material so as to be compressed under pressure of the valve. The rings are spaced to provide an annular space which communicates with the opening 15. The valve unit 16 further embodies a finger 24, one end of which is formed on the inner periphery of the valve arm adjacent the air valve 18. Said finger extends downwardly into proximity to the valve 18 and then is laterally offset and extends downwardly, terminating in a sleeve 25, which is revolvably mounted upon a shaft 26 which latter extends through the channel 11 and is engaged in the opposite walls of the casing 3.

The arcuate arm of the valve unit 16 is mounted for movement through the opening 10 of the partition 9 and is provided with notches 27 which are adapted to be engaged by a pawl 28. One end of the pawl is pivotally mounted in the partition 9 above the opening 10 while the opposite end is of a right angular configuration and adapted to engage one terminal of any one of the notches 27 in order to prevent reverse movement of the valve arm. Consequently, after the valve heads have been unseated it will be im-

possible to reseat them until the pawl 28 has been disengaged from the notch into which it has gravitated.

Upon reference to Fig. 1 of the drawings, it will be apparent that the air valve 18 is appreciably larger than the water valve 19 and the valve so positioned that the water in the chamber 8 will tend, by its own pressure, to keep the valve seated, even though some 10 of the air should be exhausted from the chamber 12. As is well known in the art, the opening 6 will be placed in communication with a source of water supply and the opening 14 placed in communication with a 15 sprinkler and a seal of any conventional design. As soon as the seal is broken air will be permitted to exhaust through the opening 14, which will permit the water pressure in the chamber 8 to move the valve 18 from its seat, thereby correspondingly unseating the valve 19 and permitting the water to pass through the opening 14 to the sprinkler and through the opening 15 to the alarm mechanism.

25 It is to be understood that the above de-

scribed device is illustrative merely of the principle of my invention and that changes may be made by me in the details of construction, proportion and arrangement of parts.

What is claimed is:

A dry pipe valve including a casing equipped with a vertical partition in its upper end to provide a pair of air compartments, the portion of the casing below said partition constituting a water compartment, a valve arm movably arranged through said partition and equipped with valves on its terminals to close communication through said compartments, and a pawl carried by the partition and automatically engageable with said valve arm to hold the latter stationary after the valves have been opened.

30 In testimony whereof I affix my signature in presence of two witnesses.

HARRY H. McCARN.
